United States Patent Office.

C. B. WALSH, OF WAUPACCA, WISCONSIN.

Letters Patent No. 95,292, dated September 28, 1869.

IMPROVEMENT IN TURBINE WATER-WHEELS.

The Schedule referred to in these Letters Patent and making part of the same.

To all whom it may concern:

Be it known that I, C. B. WALSH, of Waupacca, in the county of Waupacca, and State of Wisconsin, have invented a new and useful Improvement in the construction of Turbine Water-Wheels; and I do hereby declare that the following is a full, clear, and exact description thereof, reference being had to the accompanying drawings, and letters marked thereon, making a part of this description, in which—

Figure 1 is a representation of a turbine water-wheel, constructed according to my plan.

Figure 2, a perspective representation of the inner hoop and its flange, and shows the position and construction of a part of the buckets belonging thereto.

Figure 3, a broken view of the outer hoop and its flange, with one bucket attached.

The nature of the present invention consists in the peculiar arrangement of the buckets, hoops, rim, and flanges, whereby the construction is greatly simplified, while, at the same time, a wheel of great power and durability is produced, as the whole is hereinafter fully shown.

C, figs. 1 and 2, represents the inner hoop, cast solid with a concave flange, F, which has a height from its base to its inner periphery, which is about equal to the height of the hoop, the bottom part of said hoop being cast solid, with a bottom, through which a hole is made to receive a shaft.

Buckets K I are so formed as to fit the concave flange F and hoop C closely, as shown at fig. 2, the lower parts of the buckets K having vertical bearings against the hoop, and underlapping the upper parts at P, and being fastened to the flange and hoop, by means of bolts or screws, put through the lugs b b', are held firmly in place. And the relation of the buckets is such to each other that the water passing between them has so much space at x x, under the parts I, as not to strike the backs of the buckets and retard the motion of the wheel, while at the same time the curves V, in the faces of the buckets, so

guide the water downward, as not to break the current of water discharged from the upper casement.

The top parts I of the buckets are fastened to the hoop C, by means of bolts or screws put through the lugs h, and to the inside of the hoop B, by bolts put through the lugs f, and the upper edges of the parts K are fastened by means of screws, put through the flange E, the outer edges of said buckets being so formed as to fit the inside of the hoop B and flange E.

The buckets H J are each cast in one piece, and are so formed as to fit the flange E closely, and also fit the curve of the hoop B, to which they are fastened by means of screws, put through the lugs n, the parts J being fastened to the flange E, in the same manner as the parts K.

The wheel is now completed by putting the rim A, over the edges of those parts of the buckets shown at H, and fastening it by bolts put through the lugs m. It will be seen from this description that the two hoops, with their concave flanges, provide a convenient support for the inner and outer buckets, and that their relative size and position permit the inner buckets to take water from between the hoops B C, and yet discharge it below buckets H, at the periphery of the wheel, while at the same time the outer buckets are taking and discharging water under a like pressure.

The curbing and setting this kind of wheel are so well understood that no instructions are deemed necessary.

Having thus fully described my invention,

What I claim, and desire to secure by Letters Patent of the United States, is—

The construction and arrangement of the hoops B C, concave flanges E F, rim A, and buckets K I and H J, as set forth.

C. B. WALSH.
